TABLE

William I. Smith, Perrysburg, Ohio, assignor to Hetrick Manufacturing Company, Toledo, Ohio, a corporation of Ohio

Application October 11, 1954, Serial No. 32,616

Term of patent 14 years

(Cl. D33—14)

I claim:

The ornamental design for a table, as shown.
